US00D564318S

(12) **United States Design Patent** (10) Patent No.: **US D564,318 S**
(45) Date of Patent: **** Mar. 18, 2008**

(54) **WIRE INSULATION STRIPPING TOOL**

(75) Inventor: **Mitsuhiko Miyazaki**, Osaka (JP)

(73) Assignee: **Hakko Corporation**, Osaka (JP)

(**) Term: **14 Years**

(21) Appl. No.: **29/272,048**

(22) Filed: **Jan. 31, 2007**

(30) **Foreign Application Priority Data**

Sep. 1, 2006 (JP) D2006-023362

(51) **LOC (8) Cl. 08-05**

(52) **U.S. Cl. D8/29.1**

(58) **Field of Classification Search** D8/29.1, D8/29.2; 81/9.4, 9.44; 219/227, 229, 230, 219/232, 233, 234

See application file for complete search history.

(57) **CLAIM**

The ornamental design for wire insulation stripping tool, as shown and described.

DESCRIPTION

FIG. 1 is a perspective view of wire insulation stripping tool;

FIG. 2 is a front view thereof;

FIG. 3 is a rear view thereof;

FIG. 4 is a right side view thereof; and,

FIG. 5 is a bottom view thereof.

The portion shown by broken lines is for illustrative purposes only and forms no part of the claimed design. The dashed lines show a borderline between the claimed design and other portion.
